UNITED STATES PATENT OFFICE.

LEO ALBANESE, OF BROOKLYN, NEW YORK.

WATCH.

Application filed August 22, 1922. Serial No. 583,482.

To all whom it may concern:

Be it known that I, LEO ALBANESE, a citizen of Italy, and residing at Brooklyn, in the county of Kings and State of New York, have invented certain new and useful Improvements in Watches, of which the following is a specification, such as will enable those skilled in the art to which it appertains to make and use the same.

10 This invention relates to watches and particularly to watch case constructions, and the object of the invention is to provide an elongated watch case, which is so constructed as to receive and support in one end portion of the case a watch movement, and to receive and support in the other end portion thereof a powder puff, and also to serve as a container for powder; a further object being to provide the watch case with hinge 15 door members for controlling the insertion and removal of the watch movement and powder puff, one of said members being provided with a transparent panel through which the watch dial is visible, and the other 20 of said members being provided on its inner face with a mirror; a still further object being to provide a case construction in which the powder puff is removable from the back of the watch case, and the receptacle for the 25 powder is sealed from the watch movement receiving receptacle, and the watch movement placed therein; and with these and other objects in view, the invention consists in a watch construction of the class and for the purpose specified and which is constructed as hereinafter described and claimed.

The invention is fully disclosed in the following specification, of which the accompanying drawing forms a part in which the 30 separate parts of my improvement are designated by suitable reference characters in each of the views, and in which:

Fig. 1 is a front view of my improved watch construction.

Fig. 2 is a longitudinal sectional view through the watch case, and on an enlarged scale.

Fig. 3 is a back view of the watch as shown in Fig. 1.

Fig. 4 is a perspective detail view of the watch case, with one of the cover members thereof in an open position and,

Fig. 5 is a perspective detail view of the powder puff which I employ.

55 In practise I provide an elongated watch case 10 the contour of which may be of any

desired form and said case is provided with two substantially circular apertures or compartments, 11 and 12, the compartment 11 opening outwardly through the front face 60 of the case, while the compartment 12 opens outwardly through the back face thereof and the separate compartments are sealed one from the other by a partition wall 13.

The compartment 11 is adapted to receive 65 a suitable watch movement 14, the stem of which is adapted to enter a recess 15 in the top wall of the case 10 and said top wall is preferably provided with a suitable suspending loop 16. The compartment 11 is 70 adapted to be normally closed by a cover member 17 hinged to the bottom of the case as shown at 18 and said cover member is provided in front of the dial of the watch movement 14 with a transparent panel 19 75 through which the dial of the watch movement is visible, and this panel will conform with the formation or contour of the dial of the watch movement, which may be of any desired form.

The compartment 12 is adapted to form 80 a container for face powder, rouge or the like and is also adapted to receive a powder puff 20, said puff being shown in detail in Fig. 5 of the drawing. The compartment 12 85 is adapted to be closed by a door member 21 hinged to the back face of the case as shown at 22 adjacent to the lower end thereof, and the inner face of the cover member 21 is provided with a mirror 23.

Both of the cover members 17 and 21 are frictionally or otherwise held in a closed position, and by constructing the watch case in the manner shown and described, the powder in the compartment 12 is kept free 90 from and out of contact with the watch movement 14 in the compartment 11, said compartments being sealed one from the other, and it will be understood that while I have shown certain details of construction 100 for carrying my invention into effect, that I am not necessarily limited to these details and various changes therein and modifications thereof may be made within the scope of the appended claims without departing 105 from the spirit of my invention or sacrificing its advantages.

Having fully described my invention, what I claim as new and desire to secure by Letters Patent, is:

110 1. A watch of the class described, comprising an elongated watch case, means for

- 2
- supporting a watch movement in one end portion thereof, means for supporting a powder puff or the like in the other end portion thereof, said watch movement and 5 powder puff being insertable into the watch case through opposite side faces thereof, and door members for controlling the insertion and removal of said watch movement and powder puff.
- 10 2. A watch of the class described, comprising an elongated watch case, means for supporting a watch movement in one end portion thereof, means for supporting a powder puff or the like in the other end 15 portion thereof, said watch movement and powder puff being insertable into the watch case through opposite side faces thereof, and door members for controlling the insertion and removal of said watch movement 20 and powder puff, one of said door members being provided with a transparent panel adapted to register with the dial of the watch movement.
3. A watch of the class described, comprising an elongated watch case, means for supporting a watch movement in one end portion thereof, means for supporting a powder puff or the like in the other end portion thereof, said watch movement and 25 powder puff being insertable into the watch case through opposite side faces thereof, and door members for controlling the insertion and removal of said watch movement, one of said door members being provided with a transparent panel adapted to register with the dial of the watch movement, and the other of said door members being provided with a mirror.
- 30 4. A watch case of the class described, said case being elongated in form and provided in the opposite end portions thereof with compartments opening outwardly through the opposite side faces of said case through the opposite side faces of said case 35 and sealed one from the other.
- 45 5. A watch case of the class described, said case being elongated in form and provided in the opposite end portions thereof with compartments opening outwardly through the opposite side faces of said case and sealed one from the other, and a hinged cover member extending the full length of said watch case and provided with a transparent panel adapted to register with one of the compartments of said case.
- with compartments opening outwardly through the opposite side faces of said case and sealed one from the other, and a hinged cover member extending the full length of said watch case and provided with a transparent panel adapted to register with one of the compartments of said case. 50
6. A watch case of the class described, said case being elongated in form and provided in the opposite end portions thereof with compartments opening outwardly through the opposite side faces of said case and sealed one from the other, and a hinged cover member extending the full length of said watch case and provided with a transparent panel adapted to register with one of the compartments of said case, and a door member hinged to the other side face of the watch case and adapted to normally 55 close the other of said compartments. 60
7. A watch case of the class described, said case being elongated in form and provided in the opposite end portions thereof with compartments opening outwardly through the opposite side faces of said case and sealed one from the other, and a hinged cover member extending the full length of said watch case and provided with a transparent panel adapted to register with one of the compartments of said case, and a door member hinged to the other side face of the watch case and adapted to normally 65 close the other of said compartments. 70
8. A watch of the class described comprising an elongated watch case, one end portion of the casing being provided with a compartment opening outwardly through one face thereof and in which a watch movement is adapted to be supported, and the other end portion of the case being provided with a compartment opening outwardly through the opposite face thereof. 75
- 80
- 85
- 90
- In testimony that I claim the foregoing as my invention I have signed my name this 19th day of August 1922.
- LEO ALBANESE.
